(57) **CLAIM**

The ornamental design for a spectacle case, as shown and described.

DESCRIPTION

FIG. 1 is a perspective view in closed position of the spectacle case that comprises my invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view in open position.

The broken lines throughout the figure views show stitching which does not form a part of the claimed design.

1 Claim, 8 Drawing Sheets(56)
